UNITED STATES PATENT OFFICE.

ORVILLE F. BENNETT, OF HAVERHILL, MASSACHUSETTS.

BOILER CONNECTION.

1,334,072.

Specification of Letters Patent.

Patented Mar. 16, 1920.

Application filed July 17, 1918. Serial No. 245,353.

To all whom it may concern:

Be it known that I, ORVILLE F. BENNETT, a citizen of the United States, and a resident of Haverhill, in the county of Essex and State of Massachusetts, have invented an Improvement in Boiler Connections, of which the following is a specification.

This invention relates to connections for domestic boilers which are adapted to be made from without the boiler, the material, of which these boilers are formed, being thin and flexible sheet metal unadapted to receive a screw thread, and which must, therefore, be clamped at opposite sides.

Prior to my invention devices of this character have been produced in which a longitudinally or axially split nipple is provided which is flanged at one end to engage the inner surface of the boiler, and threaded at the other end to receive the coupling sleeve, but these devices are objectionable on account of the difficulty of holding the sections, into which the nipple is split, in such a position that the screw threads are in line, 25 so as to permit the coupling to be screwed thereon.

The object of my invention is to provide a form of boiler connection which is adapted to be placed in position and connected from outside the boiler, and in which the threaded nipple portion is of one solid piece so that the difficulty in making the connections, above noted, is avoided, said device being otherwise adapted to be easily placed in 35 position.

I accomplish these objects by the means shown in the accompanying drawing, in which:—

Figure 1 is a side elevation of a coupling embodying my invention.

Fig. 2 is a longitudinal central sectional view thereof.

Fig. 3 is an end view, and

Fig. 4 is a detail view of one of the ring 45 sections which I employ.

As shown in the drawing, the coupling comprises a nipple *a*, and a coupling sleeve *b*, said nipple having one end portion externally threaded and said sleeve having its bore internally threaded correspondingly to receive said nipple. The diameter of the nipple, at its opposite end, is somewhat less than the diameter of the aperture in the boiler *x*, in which this end of the nipple 50 is to be inserted, and the exterior surface thereof is formed to taper from said inner

end to the middle portion thereof, providing a conical face *a'*. A ring is provided which is split axially and radially and is composed of four sections *c*, identical in form, and each extending through a quadrant.

The ring formed by said sections is adapted to fit into the boiler aperture and has a flange *c'* at one end, of substantially greater diameter than the diameter of said aperture, while the bore of said ring is formed to taper from its flanged end, the conical surface thus formed being adapted to fit the tapering surface *a'* of the nipple.

The inner end portion of the sleeve, into which the nipple is adapted to be screwed, is provided with an end flange *b'* of greater diameter than the boiler aperture, the end face of the sleeve being chambered to receive a suitable packing washer *d*. The bore of the sleeve is also enlarged sufficiently to receive the ring *c*, when the parts are in position. The bore of the sleeve at its outer end is threaded to receive a connecting pipe, as indicated.

Each ring section *c* is provided with means to enable the parts to be placed in position in the boiler aperture, and the means which I preferably employ consists of angularly bent, stiff wires *e*, one of which is secured in the flanged end of each section, each wire being bent to extend radially of the ring and then at right angles through the ring, adjacent its axial, or central longitudinal line, so that, when the ring sections are 85 in position the axially extending portions will lie practically side by side, as indicated in dotted lines in Fig. 2.

In making the connection with the boiler, the ring sections are first passed separately 95 through the boiler aperture and supported within the boiler by the wires, and then the nipple *a* is passed onto the wires and into the boiler aperture, so that the enlarged end thereof extends within the boiler. The 100 sections are then drawn into position about the nipple and, with the nipple, are drawn outward until the flange engages the interior wall of the boiler, and the nipple wedges the ring sections into position, so that 105 further withdrawal of the nipple is prevented. These parts are then held in position by the wires while the coupling sleeve is passed thereon, and screwed onto the outer end of the nipple. At the same time, 110 the inner end portion of the sleeve is passed onto the outer end portion of the ring *c*,

so that the ring sections are held closely against its nipple.

To enable the sleeve to be passed onto the end of the ring without difficulty, in case one or more of the ring sections should swing somewhat out of position, the outer end of the ring is slightly beveled, and the inner end portion of the bore of the sleeve is similarly beveled, as indicated in the drawing. The parts are, however, so formed that, by the time the inner end of the sleeve has been screwed into engagement with the surface of the boiler, the straight portion of the sleeve will have been passed onto the straight portions of the ring, so that the ring sections will be positively forced into the positions of Fig. 2.

The sleeve will then be screwed firmly against the boiler, so that a tight joint will be formed therebetween, the nipple being held against rotation, when the sleeve is screwed thereon, by any suitable or convenient means. The holding wires *e* may be readily removed in any convenient manner, after the parts have been screwed together. The pipe connection may then be made with the outer end of the sleeve, as indicated.

With the above described construction a uniform bearing or support is provided at the inner side of the boiler, or tank, which engages the wall thereof continuously about the aperture therein, so that a tight joint may be formed between the coupling sleeve and the outer surface of the wall. This is a feature of great practical importance, for the reason that, on account of the thinness of the wall, it is easily bent, and, if a continuous uniform support is not provided therefor, it will not be held up firmly into engagement with the end of the sleeve, so that leakage would be caused.

I claim:—

1. A boiler connection comprising a nipple having an enlarged inner end portion, adapted to be inserted in the boiler aperture, an axially split ring adapted to encircle said enlarged inner end portion within the sides of said aperture and having a flanged end adapted to engage the inner surface of the boiler, and a coupling sleeve adapted to be threaded on the outer end of the nipple and to seat at its inner end against the outer surface of the boiler.

2. A boiler connection comprising a nipple having an enlarged inner end portion, adapted to be inserted in the boiler

aperture, a ring composed of a series of radially divided sections adapted to be disposed about said nipple in position to be internally engaged by the enlarged end-portion thereof and formed to extend between said end portion and the sides of said aperture, and to engage the inner surface of the boiler, and a coupling sleeve adapted to be threaded on the outer end of said nipple and to seat against the outer surface of the boiler, to form a tight joint therebetween.

3. A boiler connection comprising a nipple adapted to be inserted at its inner end, in the boiler aperture and formed exteriorly to taper from said inner end toward the middle thereof, a ring composed of a series of radially divided sections adapted to be interposed between said nipple and the sides of said aperture and having a tapering bore against which the tapered portion of the nipple is adapted to seat and a projecting flange to engage the interior wall of the boiler, and a coupling sleeve adapted to be threaded on the outer end portion of said nipple and to seat against the exterior of the boiler.

4. A boiler connection comprising a nipple having an enlarged inner end portion, adapted to be inserted in the boiler aperture, an axially split ring adapted to encircle said enlarged inner end portion within the sides of said aperture and having a flanged end adapted to engage the inner surface of the boiler, and a coupling sleeve adapted to be threaded on the outer end of the nipple and to fit onto the outer end portion of said ring and seat against the outer surface of the boiler to form a water tight joint therewith.

5. A boiler connection comprising a nipple having an enlarged inner end portion, adapted to be inserted in the boiler aperture, an axially split ring adapted to encircle said enlarged inner end portion within the sides of said aperture and having a flanged end adapted to engage the inner surface of the boiler and a coupling sleeve adapted to be threaded on the outer end of the nipple and to seat against the outer surface of the boiler, and temporary supports for each of said ring sections arranged to extend about the inner end of said sleeve and through the bore thereof.

In testimony whereof I have signed my name to this specification.

ORVILLE F. BENNETT.
